SUSPENSION HOOK FOR A CLOTHES HANGER ROD

Carl E. Gingher, 304-328 Depot St., Scranton, Pa.

Filed Sept. 11, 1964, Ser. No. 81,682

Term of patent 14 years

(Cl. D33—8)

FIG. 1

FIG. 3

I claim:

The ornamental design for a suspension hook for a clothes hanger rod, as shown.
